GLASS HOLDING RACK FOR A DISHWASHER

Walter J. Keen, Lower Hutt, New Zealand, assignor to Dishmaster Appliances Limited, Wellington, New Zealand, a corporation of New Zealand

Filed Oct. 27, 1967, Ser. No. 9,190

Claims priority, application New Zealand June 9, 1967

Term of patent 14 years

U.S. Cl. D49—1
Int. Cl. D7—06

I claim:

The ornamental design for a glass holding rack for a dishwasher, as shown.
